57.

John G. Thomas, Winchester Ohio.

Letters Patent.

The Schedule agreeable to in these Letters Patent and making part of the same containing a description in the words of the said John G. Thomas himself of his improvement in the Churn.

Be it known that I John G. Thomas of the town of Winchester in the County of Pendle and State of Ohio, have made and now have a useful improvement in the Churn, which is described as follows:—Reference being had to the annexed drawing of the same, in making part of this specification. This improvement consists in having a water tight box A about two feet long, one foot wide, and one foot six inches deep, or of any convenient size, covered tightly with a cover or lid B, within this box are placed parallel to each other two shafts C C, turning on cog gears in holes, made in slices D D D D, let into notched grooves in the sides of the box. In to these shafts are inserted a convenient number of rachels or arms E, working between each other, and in the ends of said shafts are cog wheels F F, working into each other, turning them in any contrary directions. Above and working into one of these cog wheels is a larger cog wheel G turning on a shaft H, which projects through the side of the box sufficiently to receive a crank handle I by which it is turned. The lid being removed the cover is fastened to the box and the lid is replaced and covered, the crank handle is then turned, which turns the larger cog wheel, this turns the small cog wheel which turns the other small cog wheel and thus the shafts and rachels are turned in opposite directions, which will turn the cover and form the butter. The lid is again removed and the shafts and cog wheels taken

These boxes from the body by raising the dovetailed slides from the grooves. The box is then emptied of its contents in the most convenient manner. The shafts may be turned in a vertical position with the cog wheels working horizontally on the outside of the box as at K.

What I claim as my invention and desire to be secured by Letters Patent, consists in the arrangement and adaptation of the several parts of the before described机关.
